UNITED STATES PATENT OFFICE

SAMUEL P. BUSH, OF COLUMBUS, OHIO, ASSIGNOR TO THE BUCKEYE STEEL CASTINGS COMPANY, OF COLUMBUS, OHIO

CAR-TRUCK CONSTRUCTION

Application filed December 21, 1926. Serial No. 156,169.

This invention relates to car trucks of that type in which the truck bolster and bolster support may swing laterally with respect to the side frames, the object being to provide a 5 novel construction whereby the transoms and hangers will be supported within the side frames so that, in the event of breakage, the parts will be caught in the side frame and will not drop onto the track to derail the car. 10 The invention is illustrated in the accompanying drawing and resides in certain novel features which will be first fully described and then more particularly defined in the appended claims.

15 In the drawing, Figure 1 is a side elevation of a portion of a car truck embodying the invention;

Figure 2 is a view showing the side frame in transverse section and the end of the 20 bolster and associated parts in elevation;

Figure 3 is a view partly in plan and partly in section on the line 3—3 of Figure 1;

Figure 4 is a section on the line 4—4 of Figure 1;

25 Figure 5 is an elevation of an end portion of a transom;

Figures 6, 7 and 8 are views corresponding to Figs. 1, 2 and 3, respectively, showing a modification;

30 Figures 9 and 10 are detail views showing a further modification.

Referring particularly to the illustration, the numeral 1 designates a side frame having a lower member 2, an upper member 3, and columns 4 connecting said members, the arrangement providing an opening 5 receiving the end of the bolster 6 and the spring carrier 7. The opening 5 also accommodates the hangers 8, one at each side of the bolster and the spring carrier, and just below the upper member 3, the columns 4 are inset to define recesses 9 receiving the ends of the transoms 10 which connect the two side frames. It will be noted that the transoms rest on shoulders 11, formed on the columns 4, and are provided on their under sides with lugs 12 engaging in sockets provided therefor in the shoulders whereby separation of the transoms transversely from the side frames is prevented. In their upper edges, adjacent their

ends, the transoms are formed with concave notches 13 forming seats for pins 14 which pass through the upper ends of the hangers to pivotally suspend the latter, said pins being inserted through and supported by lugs or webs 15 depending from the upper member 3 of the side frame. The lugs or webs 15 and the columns 4 effectually prevent movement of the hangers and transoms longitudinally of the side frames, and, to support the brake mechanism in fixed position on the truck, brake hanger brackets 16 are formed integral with the transoms. As shown most clearly in Fig. 1, the lugs 15 are provided on their inner sides with stop lips 15¹ to prevent endwise movement of the pins 14, the pin dropping behind the lip, as it is put in place, in an obvious manner. The lower ends of the hangers receive trunnions 18 on the spring carrier 7 whereby said carrier will be supported by the 55 hangers and may have some swinging movement. To reinforce the side frames and more effectually withstand the impact of the hangers and spring carrier, in the event that some accident should cause them to fall, the 60 ribs 19 are formed on the lower member 2 of the side frame at the base of each column 4. The side frame is preferably provided 65 on its inner side with inwardly projecting stop arms or brackets 20 which extend along- 70 side the bolster to guide it sidewise and effectually resist the reactions due to forces trans- 75 verse of the bolster. These arms or brackets may, however, be omitted in small trucks in- tended for light service.

80 Instead of the hangers 8 which are in the form of elongated loops, the hangers 21, shown in Figs. 6, 7 and 8, may be employed. The hanger 21 consists of a bar tapered to- 85 ward its lower end and provided with the slot 22 in its upper portion whereby it may be pivotally suspended on the pin 14, as in the previously described form of the invention. At its lower end, the hanger 21 is provided with a crosshead or stud 23, and 90 the spring carrier 24 is provided with a lug 25 on its side having a notch 26 in its lower edge to engage over the crosshead 23, the crosshead being circular in cross section 95 whereby the spring carrier may have rela- 100

tive rocking or pivotal movement, as will be understood on reference to Fig. 7. The lug 25 is in the form of a bail as shown in Fig. 8, being open at top and bottom and of proper dimension to permit the hanger to be inserted upwardly therethrough in assembling the parts. The column of the side frame is offset, as at 27, to accommodate the greater width of the lug 25 and the outer side of the lug provides an extended wearing surface against the wall of the bolster opening.

The transoms may be cast in one integral unit, the two side members 30 being connected by a horizontal plate or web 31, as indicated in Fig. 7.

In the form shown in Figures 9 and 10, the hanger 8 of the first-described form is used, but the trunnion on the spring carrier 28 is formed at its outer end with a head 29 which is laterally elongated, as shown in Fig. 10, whereby it will retain the hanger on the trunnion and will also furnish the desired wearing surface.

The improved construction herein shown and described minimizes the number of necessary parts and produces a compact and strong truck which will possess the desired swinging characteristic of the bolster and its support while preventing such excessive movement as might cause separation of the parts.

Having fully described my invention what I claim as new and desire to secure by Letters Patent, is:—

1. In a car truck construction, a side frame having columns provided at their upper ends with transverse shoulders and sockets in the shoulders, hangers pivotally suspended in the frame, a spring carrier supported by the hangers, and transoms having their ends resting on said shoulders and provided on their under sides with lugs engaging in said sockets the transoms being further provided with recesses in their upper sides to accommodate and support the hanger pivots.

2. In a car truck construction, a side frame having a bolster opening, hangers pivotally suspended in the opening of the side frame, and a spring carrier disposed between the hangers, trunnions connecting said carrier and hangers, there being wear surfaces on the trunnions to prevent the hangers from wearing against the sides of the bolster opening.

3. In a car truck construction, a side frame having a bolster opening, hangers pivotally suspended in the opening of the side frame, and a spring carrier pivotally mounted in the hangers, there being wear surfaces on the sides of the hanger connection of the spring carrier to prevent the hangers from wearing against the sides of the bolster opening.

4. The combination of a car truck side frame including columns spaced apart, shoulders formed on the upper portions of said columns and provided with sockets, transoms supported by said shoulders and having lugs

engaging the sockets in the shoulders, hangers, pivot pins for said hangers, said pivot pins resting upon said transoms, supports for said pivot pins depending from the upper portion of the side frame, a spring carrier supported by said hangers, and a bolster entering between said columns above the spring carrier.

5. The combination of a car truck side frame including columns spaced apart, shoulders formed on the upper portions of said columns, transoms supported by said shoulders, hangers, pivot pins for said hangers, said pivot pins resting upon said transoms, supports for said pivot pins depending from the upper portion of the side frame, stops on said supports for said pivot pins, a spring carrier supported by said hangers, and a bolster entering between said columns above the spring carrier.

In testimony whereof, I have signed this specification.

SAMUEL P. BUSH.
